COSMETIC ASSEMBLY

Henry Fitz, Washington, D. C., assignor to Fitz Cosmetics Incorporated, Washington, D. C., a corporation of Delaware

Application July 13, 1950, Serial No. 173,502

3 Claims. (Cl. 132—79)

1

The present invention relates to a cosmetic assembly and more particularly to a lipstick holder combination with a mirror or compact holder.

It is well known that in attempting to select the proper shade or color of lipstick from a counter, the purchaser frequently extracts the lipstick from its container and rubs off a small sample portion to determine whether the shade or color is that desired, and if the particular color tried is not pleasing to the customer, she puts the lipstick back in place and samples another lipstick until one is found which appears to be satisfactory. This common practice is unsanitary and is especially objectionable to the more fastidious persons or discriminating customers and results in loss of sales where this practice is known to be followed.

One of the objects of the present invention is to provide a form of lipstick holder which is readily held in place on a mirror in position for immediate use and in connection with which the color of the lipstick contained in the holder is indicated in a manner so as to avoid trial or sampling the lipstick to determine the color or shade.

Another object of the invention is to provide a form of lipstick holder having spring-pressed gripping means by which the holder may be readily attached to a mirror of the usual form and which includes attaching means by which a color designation may be applied to the gripping means or readily changed to indicate the particular color or shade of the lipstick enclosed within the holder.

Another object of the invention is to provide a means and method for attaching a lipstick holder to a vanity case or compact holder, by which the lipstick holder may be attached in the particular position on the vanity case or compact holder which is best suited to the individual by whom the article is to be used.

Another object of the invention is to provide a lipstick holder of a form adapted to be applied to the periphery of a vanity case or cosmetic holder adjacent to the locking means therefor so that by pressing the lipstick holder inwardly, the vanity case or cosmetic holder is opened.

With these and other objects in view, the invention comprises various features and combinations hereinafter described and illustrated in the accompanying drawings.

Referring to the drawings,

Fig. 1 is a view in elevation showing a lip-

2

stick holder of the invention combined with the usual form of ladies' mirror;

Fig. 2 is a cross sectional view taken on the section line 2—2 of Fig. 1;

5 Fig. 3 is an enlarged detailed view in elevation of one of the guards or attaching means to be applied to one of the gripping elements attached to the lipstick holder;

Fig. 4 is a cross sectional view taken on the 10 section line 4—4 of Fig. 3;

Fig. 5 is view in elevation of a modified form of lipstick holder having integral metal spring-pressed gripping means for attaching or securing the holder to a mirror;

15 Fig. 6 is a cross-sectional view taken on the section line 6—6 of Fig. 5;

Fig. 7 is a view in elevation of a second modification of the lipstick holder of the invention;

Fig. 8 is a cross sectional view taken on the section line 8—8 of Fig. 7;

20 Fig. 9 is a view in elevation of a form of gripping means which is adapted to be attached to a lipstick holder casing by means of an elastic band which may be adjusted to accommodate the circumference of any lipstick holder casing;

Fig. 10 is a cross sectional view taken on the section line 10—10 of Fig. 9;

Fig. 11 is a view in elevation of a form of lipstick holder casing made integral with the frame of a circular form of mirror, and

25 Fig. 12 is a fragmentary cross sectional view taken on the section line 12—12 of Fig. 11;

Fig. 13 is a plan view showing a portion of a vanity case having a lipstick container casing attached to the bottom of the vanity case by attaching means securing the lipstick container casing in any desired position at the periphery of the casing;

30 Fig. 14 is a plan view of a form of vanity case and lipstick container casing combination in which the lipstick casing is associated with the locking means for locking the cover of the vanity case, so that the cover may be opened by merely pressing the lipstick container casing inwardly;

Fig. 15 is a detailed fragmentary exploded view of the underside of the vanity case shown in Fig. 14, showing the guide element cemented in place on the vanity case and the lipstick container casing and slide or extension for locking the lipstick casing in place in the guide member;

Fig. 16 is a cross sectional view taken on the section line 16—16 of Fig. 15;

Fig. 17 is a fragmentary exploded plan view showing the underside of the vanity case of Fig. 14 with a modified form of connection for de-

tachably connecting the lipstick container casing to the vanity case, and

Fig. 18 is a fragmentary detailed view taken on the section line 18—18 of Fig. 17.

Referring more in detail to the drawings, the numeral 2 designates a lipstick container casing having a lipstick tube and lipstick 4 therein, the lipstick container casing being attached to a mirror 6, such as a pocket mirror or a rear-view mirror of an automobile, by means of segmental spring-pressed gripping means 8 and 10, which are adapted to be covered by means of a coloring material, as paint or dye, or by means of a thin guard member or casing 12, of plastic material which is adapted to be colored the same color or shade as that of the lipstick 4 carried in the lipstick container casing. By making the casing members or guards 12 of the size and shape to fit over the gripping means for attaching the lipstick container casing to the mirror, the guards may be colored in place of coloring the gripping members, thus avoiding the sampling or trial of the lipstick in order to determine whether the lipstick color or shade is that desired. The casing members or guards 12 may be made of any suitable plastic material adapted to be molded or pressed into the desired form, such as "Plexiglas," for example, which is methyl methacrylate, and may be purchased on the market in varying thicknesses and shades of color, and may readily be colored by means of a paint or pigment or dye to obtain any desired color or shade of color.

In the form of the invention shown in Figs. 5 and 6, the lipstick container casing may be stamped in a single stamping operation from metal in one piece so as to be provided with a longitudinal slit or opening 14 extending at the top of the casing so as to provide for expansion of the casing when a lipstick tube is inserted therein, so that the container casing is adapted to fit substantially any size of lipstick tube to be inserted into the casing.

The segmental gripping members 8' and 10' are preferably composed of a spring metal so as to firmly hold the lipstick container casing in place on a mirror by clamping action and the surfaces in contact with the mirror surfaces may be roughened so as to more firmly hold the gripping surfaces in place on the mirror, and the outer surfaces of the gripping members may also be roughened so that it may be more readily painted or dyed to the color of the lipstick to be held in the casing, which will serve not only in indicating the color of the lipstick when the article is purchased but will also assist in indicating the color of the lipstick when a person desires to vary the color of her makeup, depending on whether the lipstick color is to be used under artificial light or in daylight. It is sometimes desirable to carry a variety of colors of lipstick for makeup, as for use on weekend parties and trips to the seashore, for example, and the selection of the desired colors and shades may then be readily made from the owner's stock of lipsticks by the mere inspection of the depending colored gripping members of the casing carrying the color of each individual lipstick contained in the corresponding casing.

For use by younger girls and persons of insufficient means to purchase the more expensive lipstick carrying cases, a relatively inexpensive form of the invention may be used, which is illustrated in Figs. 7 and 8 of the drawings, in which the lipstick container casing and seg-

mental gripping members may be made of stamped metal or of molded hard rubber or similar compositions having the desired resilience particularly in the gripping members 8'' and 10'', so as to apply sufficient force to adhere readily to the surface of a mirror, and also to provide sufficient resilience in the container casing 2'', or provide sufficient expansion for the insertion of a lipstick tube 16 to be held thereby, the tube 16 containing a lipstick of the same shade or color as the colored area 18 on one of the segmental gripping members, as 10'', for example. In this form of the invention, the gripping element 10'' may be stamped out from the metal forming the gripping element 8'', and bent outwardly and downwardly, as shown in Fig. 8, whereby a single sheet of metal serves to simultaneously form the two segmental gripping elements, which are separated a distance corresponding substantially to the thickness of the ordinary pocket mirror.

The forms of the invention above described are particularly useful for use with mirrors, preferably of the rectangular form, which may be kept in a ladies' handbag, such as are generally carried, and the lipstick container casing may serve as a holding means for the mirror while makeup is being applied, so that the surface of the mirror does not become soiled or fogged during use or in ordinary handling. In the use of this form of the invention with the rear-view mirror of an automobile, the lipstick container casing may be retained by the segmental gripping means on the bottom edge or preferably on the right vertical edge of the mirror so as to be accessible continuously for use.

Referring to Figs. 9 and 10 of the drawings, it may sometimes be desirable to employ separate spring-pressed gripping means 20 and 22, which may be made integral by means of a bridge member 24 carrying handles 26 and 28, to which an elastic band 29 may be attached and made adjustable so as to fit a lipstick holder, which may thus be attached to a mirror in substantially the same manner as the gripping members above described. It will be apparent also that the combined gripping device and fastening means 29 may be used for attaching any small cylindrical article or article of small external dimensions to a pocket mirror or other article of narrow thickness. It may be used if desired for attaching a pencil to a small note book, for example, or for other similar uses, as will be apparent to those skilled in the art.

Shown in Figs. 11 and 12 of the drawings is a form of lipstick holder which may be made integral with the metal framework of a circular mirror and which extends from the line of attachment to the said frame in a cylindrical plane, leaving a space 30 to provide for expansion when a tube 32 carrying a lipstick therein is inserted into the carrier casing 34. This form of the invention is adapted for use more particularly for young girls or children of school age, and is relatively inexpensive to make.

The various forms of the invention above described may be varied to some extent to suit particular needs and greater or less refinement, depending on the demands of the particular groups or classes for whom the articles are designed or made. For the more fastidious persons, the form of the invention shown in Figs. 1 to 4 is better suited than those of the other forms illustrated, although it will be obvious that the same degree of refinement in manufacture may be used as is

applied to costume jewelry and other similar articles.

Referring more in detail to Figs. 13 and 14 of the drawings, a lipstick frame member 40, containing a lipstick tube 42, from which a lipstick may be extracted by means of the head 44, is securely attached to one side of a vanity case 46 by means of a perforated extension 48, which may contain perforations 50, preferably in the form of elongated slits, although the perforations may be circular or any other desired form. The lipstick frame member 40 may be attached to the vanity case in any desired position, preferably in the position in which the lipstick is most accessible to the user, depending on whether the person is right-handed or left-handed, and on the position of the cover lock of the case.

In order to permit the purchaser to attach the lipstick holder in the position on the vanity case best suited to the individual, the lipstick container 40 and the holding means or perforated extension may be purchased separate from the vanity case and readily attached in the desired position. For this purpose, a suitable solvent for lacquer may be used to wet the bottom or face of the extension 48 so that when the extension is pressed onto the bottom face of the vanity case near the periphery of the case, the lipstick container will be immediately attached without difficulty. It will be understood that substantially all vanity cases now on the market carry a lacquer coating over the entire outer surface of the vanity case, and any suitable solvent, such as amyl acetate, acetone or ethyl acetate may be used. The lacquer most generally used for this purpose is nitrocellulose, and a lacquer enamel is a lacquer which contains a pigment. A low-boiling solvent, that is, one boiling below 100° C., such as acetone and ethyl acetate, or mixtures thereof, are preferably used, although a medium boiling solvent, that is, one boiling between 100° and 150° C., such as amyl acetate, Cellosolve, butyl acetate or butyl propionate may be used. For convenience, however, it is found that nail polish remover, such as is used in any boudoir or bath room, such as "Cutex," for example, serves the purpose admirably and dissolves the lacquer by the use of a single drop so that the extension adheres to the face of the vanity case with such a strong bond that it cannot be removed by force, at least without the application of additional solvent. The perforations 50 in the extension 48 permit the spreading of the solvent over the connecting surface and allows the solvent to be evaporated almost immediately through the openings. The elongated slits as illustrated in Fig. 13 have been found best suited for this purpose, but it will be obvious that other forms or other perforations may be used to advantage to accomplish the same results.

In the form of the invention illustrated in Fig. 14, the lipstick container 40' may be attached to the vanity case 46' adjacent the locking device 52, by which the vanity case cover 54 is locked through the slit opening 56 in the periphery of the cover. The locking device 52 does not form a part of the present invention, but will be understood to comprise a spring member 58 pivoted or attached by means of the pin member 60, a detent 62 being provided on the spring member 58 to engage the slit opening or projection 56, by means of which the cover of the vanity case is locked in position.

In order to have the locking device 52 operated by pressing the lipstick container 40', a slide or

extension 64 is integrally attached to the lipstick container, the slide 64 being of a width and length so as to be adapted to slide in a guide member 66, having lateral grooves or guides 68 and 70 adapted to fit the thickness of the metal of the slide member. The guide member 66 is preferably provided with perforations 72 so that the guide member may be attached in position adjacent the locking device 52 by means of a solvent for the lacquer coating of the vanity case in the manner above described in connection with the extension 48. In order to prevent the lipstick container 40' from dropping out of the guide member 66, or being accidentally removed therefrom, an opening 74, preferably rectangular in shape is provided in the outermost part of the slide member 64, and a corresponding projection 76 is provided at the innermost part of the guide member 66, so that when the slide 64 has been pressed inwardly sufficiently, the projection 76 will engage in the opening 74 and prevent the slide member and lipstick casing from being accidentally removed from the vanity case. When it is desired to disconnect the lipstick casing 40' from the vanity case 46', the spring projection 76 is pressed downwardly and the lipstick casing is pulled outwardly at the same time until the opening 74 is disengaged from the projection 76, and the slide 64 is drawn out of the guides 68 and 70.

The opening 74 is made large enough so that when the slide member 64 is in place in the guide member 66 and the spring extension 76 is engaged in the opening 74, sufficient play is allowed so that the lipstick container 40' may be moved inwardly sufficiently to release the opening or indentation 56 from the detent 62, by which the cover member 54 is unlocked.

Referring to Figs. 17 and 18 of the drawings, the numeral 80 designates a modified form of guide member having a central rectangular opening 82 and lateral grooves or guides 84 and 86 in which the slide member 88, attached to the lipstick casing 90 is adapted to pass through the opening 92, shown in Fig. 18 of the drawings. When the slide member 88 is in position in the guide member 80, the projection or tongue 94 locks the lipstick casing 90 in the guide member 80. When it is desired to separate the lipstick container casing from the vanity case, the lipstick container casing 90 may be readily withdrawn by simply depressing the tongue member 94 and withdrawing the slide member 88 through the opening 92 while the tongue member remains depressed. The guide member 80 is adapted to be accurately cemented in place adjacent the locking device 52' on the back of the vanity case 46' by means of downwardly projecting tabs or flaps 96 and 98, which serve as guides in positioning and centering the guide member 80 directly over the latch by which the cover member of the vanity case is released, so that when the lipstick container casing is in place adjacent the latch or locking device 52', all that is necessary in order to unlock the vanity case cover is to depress the lipstick container casing 90 inwardly, which releases the slit opening or projection 56 from the detent 62, as is apparent from Fig. 14 of the drawings.

It will be understood that various changes and modifications may be made in the various forms of the invention above described without departing from the spirit or scope of the invention as defined in the claims annexed hereto, and I do not wish to be limited or restricted to the specific

details herein set forth, but wish to reserve to myself any and all variations or modifications as may be apparent to those skilled in the art within the scope of the said claims.

Having thus described the invention, what is claimed as new is:

1. A lipstick container and mirror combination which comprises an expansible unitary lipstick container casing, a metal framework for a circular mirror made integral with said casing, a circular mirror in said framework, said casing extending from the line of attachment to said framework in a substantially cylindrical surface and terminating in a free edge corresponding to an element of the cylindrical surface so as to provide a substantially rectilinear space for circumferential expansion when a lipstick tube is inserted into said container casing and means for holding the mirror in place within said metal framework.

2. The combination of a lipstick holder and mirror which comprises a metal framework for a mirror, a mirror therein, a substantially cylindrical spring metal carrier casing integrally united to said framework and extending from the line of attachment thereto in a cylindrical plane and leaving an open space to provide for circum-

5

25

ferential expansion when a lipstick tube is inserted into said carrier casing.

3. The combination of a lipstick holder and mirror which comprises a metal framework for a circular mirror, a circular mirror therein, a substantially cylindrical spring metal carrier casing integrally united to said framework and extending from a straight line of attachment thereto in a cylindrical plane and leaving an open rectilinear space to provide for circumferential expansion of the cylindrical walls of the carrier casing when a lipstick tube is inserted into said carrier casing.

HENRY FITZ.
